United States Patent Office

Des. 200,884

Patented Apr. 13, 1965

200,884

SEALING CAP

Arthur Le Roy Hart, Cary, Ill., assignor to American Can Company, New York, N.Y., a corporation of New Jersey

Filed May 13, 1964, Ser. No. 79,970

Term of patent 14 years

(Cl. D58—26)

Fig. 1

Fig. 2

FIG. 1 is a perspective view of a sealing cap embodying my new design; and

FIG. 2 is a perspective view showing the sealing cap inverted and rotated 180°.

I claim:

The ornamental design for a sealing cap, substantially as shown.
